UNITED STATES PATENT OFFICE

112,653

DESIGN FOR LACE INSERTION

Joseph Englander, New York, N. Y.

Application October 18, 1938, Serial No. 80,527

Term of patent 3½ years

To all whom it may concern:

Be it known that I, Joseph Englander, a citizen of the United States, residing at 202 West 40th Street, in the county, city, and State of New York, have invented a new, original, and ornamental Design for a Lace Insertion, of which the following is a specification, reference being had to the accompanying drawing, forming a part thereof.

The figure of the drawing is a plan view of the lace insertion showing my new design.

I claim:

The ornamental design for the lace insertion, as shown.

JOSEPH ENGLANDER.
